US0D1022786S

(12) **United States Design Patent** (10) **Patent No.:** **US D1,022,786 S**
(45) **Date of Patent:** **** Apr. 16, 2024**

(54) **TERRARIUM**

(71) Applicant: **Fang Li**, Zhaoqing (CN)

(72) Inventor: **Fang Li**, Zhaoqing (CN)

(**) Term: **15 Years**

(21) Appl. No.: **29/919,031**

(22) Filed: **Dec. 1, 2023**

(51) **LOC (14) Cl.** **11-02**

(52) **U.S. Cl.**

USPC **D11/145**

(58) **Field of Classification Search**
